BICYCLE-BRAKE.

1,169,971.

Specification of Letters Patent.

Patented Feb. 1, 1916.

Application filed July 6, 1914. Serial No. 849,146.

To all whom it may concern:

Be it known that I, ANTOINE LARRIBE, a citizen of the Republic of France, residing at 58 Rue Cambronne, Paris, France, have invented certain new and useful Improvements in Bicycle-Brakes, of which the following is a specification.

This invention relates to a bicycle brake adapted to be fitted either on the front or 10 on the back wheel although it is generally preferable to fit it on the front wheel.

This brake which is intended to act on the rim, comprises two shoes one of which is rigidly secured to one of the branches of 15 the fork so that its friction surface is in close proximity to the rim, for instance at a fraction of a millimeter while the other shoe is movable and carried by an arm mounted on the other branch of the fork 20 in such a manner that it can be brought nearer to or separated from the first shoe; when the second shoe is applied on the rim it causes the latter to bend slightly so that it bears on the opposite shoe; both faces of 25 the rim are then subjected to the same degree of friction. As the position of the stationary shoe can be adjusted as desired with a great amount of precision, the bending of the wheel can be reduced to the de- 30 sired extent, for instance, to a fraction of a millimeter so that the wheel is not strained. This disposition enables a very strong and durable brake to be obtained owing to the rigidity of one of the shoes and the simple 35 control of the other.

The invention resides also in particular dispositions of the controlling and adjusting means for the brake as will be described hereinafter with reference to the accompanying drawing, in which the figure is a fragmental front elevation showing the application of the brake to the front wheel of a bicycle.

1 designates the fixed brake shoe, the lug 45 2 of which is fixed by a bolt 3 to a flanged collar 4 fitted on one of the branches 5 of the fork of the steering wheel. A slot formed in the lug 2 or in the collar 4 for the passage of the bolt 3 permits a very accurate adjustment of the position of the 50 shoe 1 at a very small distance from the rim 6; the bending of the wheel under the pressure exerted by the opposite shoe will be thus arrested and limited to as small a degree as may be desired, thereby enabling a 55

very effective braking action to be obtained without straining the wheel.

The movable shoe 7 is fixed by means of a bolt 8 to a lever 9 adapted to rock about a pin 10 provided on a flanged collar 11 60 fitted on the other branch 12 of the fork. The movable shoe is positioned in such a manner as to bear on the side of the rim 6 opposite to the shoe 1 when the traction rod or the like 13 of the lever 9 is drawn upwardly in opposition to the action exerted by the spring 14 secured to the shoe 1. Slots formed in the rear end of the shoe 7 and the lever 9 for the passage of the bolt 8 permit of adjusting the position of the shoe 7 with 70 great precision.

The traction rod 13 terminates at its top in a hook 15 adapted to interchangeably engage the links of a small chain 16 secured to the controlling handle 17, the latter being 75 fitted pivotally on the handle bar. This permits the lever 9 to be instantly released for instance, when it is desired to withdraw the wheel from the fork 5-12 and also to adjust roughly the length of the controlling 80 means. The latter may be accurately adjusted owing to the fact that the rod 13 is divided into two parts which are adjustably connected by means of an ordinary turn-buckle 18; this sleeve turn buckle is located 85 near to the handlebar so that the rider may operate same without dismounting and adjust the brake while cycling.

It is obvious that the shoes may be made of any material and fitted in any manner 90 to the fork; its shape as well as that of the lever 9 and the collars 4 and 11 may be modified. The shoes in particular will be given a shape in accordance with the section of the rim which may be of any type. 95

The means for controlling the position of the shoes or the position of the axis of the lever or levers, the point at which the spring or springs are secured, the length of the controlling rod and so on, may be varied 100 as desired. Where the brake is fitted to the back wheel the rod 13 will be replaced by a suitable transmission mechanism, with or without a flexible cable.

Claims:

1. In a bicycle brake, the combination of a lever pivotally connected to one branch of a fork of the frame and having a slot at one terminal thereof, a shoe having a slot therein, means passing through the slots of 110

the lever and shoe for adjustably connecting the shoe to the lever, and means for operating the lever for causing the shoe to be forced into engagement with the rim of a wheel for retarding the momentum thereof.

2. In a bicycle brake, the combination of a fixed shoe adjustably connected to one branch of a fork of the frame, and in a position to be engaged by the rim of the wheel, a lever pivotally connected to the other branch of the fork and having a slot formed in one terminal thereof, a movable shoe having a slot formed therein, means passing through the slots of the lever and movable shoe for fastening them together, and means for operating the lever for causing the movable shoe to be forced into engagement with the rim of the wheel and press the rim into contact with the fixed shoe, whereby the rotation of the wheel may be retarded.

3. In a bicycle brake, the combination with the fork of a frame, of a collar connected to one branch of the fork, a fixed

shoe adapted to be positioned for engagement with the rim of a wheel straddled by said fork, and having a slot therein, means passing through the slot and connected to the collar for adjustably fastening the fixed shoe to the collar, a lever pivotally connected to the other branch of the fork, and provided with a slot at one terminal thereof, a movable shoe having a slot therein, means passing through the slots of the shoe and lever for connecting the shoe to the lever, and adjustable means connected to the other terminal of the lever for actuating the lever to cause the movable shoe to be forced into engagement with the rim of the wheel and press the rim into engagement with the fixed shoe, whereby the rotation of the wheel may be retarded.

In testimony whereof I affix my signature in presence of two witnesses.

ANTOINE LARRIBE.
